UNITED STATES PATENT OFFICE.

WILLIAM C. DEANE, OF WASHINGTON, DISTRICT OF COLUMBIA, ASSIGNOR TO THE HARRIS AUTOMATIC PRESS COMPANY, OF NILES, OHIO, A CORPORATION OF OHIO.

BEARER FOR PRINTING-PRESSES.

No. 923,415.

Specification of Letters Patent.

Patented June 1, 1909.

Application filed May 9, 1908. Serial No. 431,792.

To all whom it may concern:

Be it known that I, WILLIAM C. DEANE, of Washington, District of Columbia, have invented certain new and useful Improvements in Bearers for Printing-Presses; and I do hereby declare the following to be a full, clear, and exact description of the invention, such as will enable others skilled in the art to which it appertains to make and use the same.

The primary object of this invention is to provide a bearer which, while avoiding all possibility of blurring, will be strong and lasting and in no way injure the surface with which it engages and may be readily secured to or detached from a press cylinder at any desired point thereof.

The invention will be hereinafter fully set forth and particularly pointed out in the claims.

In the accompanying drawings, Figure 1 shows my improvement applied to a rotary press. Fig. 2 is a central longitudinal sectional view of the bearer detached. Fig. 3 is a similar view showing a slight modification. Fig. 4 is a view in perspective of the form used with bed and cylinder presses.

I have found by actual practice that the best possible results are attained by forming the bearer wholly or primarily of raw-hide or leather. In some instances the raw-hide may form the facing for a backing of metal, or other suitable material.

Referring to the drawings, in Fig. 1 I have shown a curved bearer secured to the plate cylinder 1 of a rotary press such bearer being shown as composed of face 2 of raw-hide secured to a metallic backing 3 by rivets 4. Suitable holes 5 are formed in the bearer to accommodate screws by which it may be secured to the cylinder at any desired point thereof. The bearer as a whole must not be more than plate high. If desired, two thin coöperating bearers may be employed, each being attached to one of the cylinders.

In bed and cylinder presses, the bearer is preferably of oblong formation, as shown in Fig. 4, so that it may be secured to the bed, but when attached to the cylinder it will, of course, be curved as is required in rotary presses.

By making the bearers wholly or pri-

marily of raw-hide I avoid the difficulty that arises from the use of bearers which cause wear of metallic surfaces with which they engage; and I am enabled to successfully overcome all danger of blurring. It will be understood that the bearer may be one continuous part, or in several independent sections located at such points as may be required relative to the type plate.

While I have found that raw-hide is best suited for accomplishing the purpose of my invention, yet any kind of leather may be used with substantially the same result. It will be understood, therefore, that in using the word "raw-hide" in both the specification and the claims I intended to comprehend the use of any kind of leather.

A bearer composed entirely of raw-hide as shown in Fig. 3, will serve every desired purpose, yet it is preferable to have a thin base of metal so as to enable the device to be readily attached to a press. Furthermore the facing of a single layer of raw-hide is less likely to separate from a metallic base than when such base is composed of a series of layers of the same material as the facing. It is also cheaper to renew the single facing in the event of wear.

I claim as my invention:—

1. A bearer for preventing blurring in printing, comprising a base designed to be attached to a portion of one of two coöperating members of a printing press, said base having an outer facing of raw-hide, and means for detachably securing the bearer at any desired point relative to the type plate.

2. A bearer for preventing blurring in printing, comprising a base designed to be attached to one of two coöperating members of a printing press composed of a metallic base and a facing therefor of raw-hide, and means for detachably securing said bearer at any desired point on such member relative to the type plate.

In testimony whereof, I have signed this specification in the presence of two subscribing witnesses.

WILLIAM C. DEANE.
